COMBINED DISPLAY AND DISPENSING
STAND FOR DICE

Chris Buizzo, 55 Porter St., Cranston, R.I. 02910

Filed Aug. 20, 1968, Ser. No. 13,199

Term of patent 14 years

Int. Cl. D6—01

U.S. Cl. D80—9

FIG. 1

FIG. 2

FIG. 3

FIG. 4

FIG. 5

FIG. 6

FIG. 1 is a front elevational view of a combined display and dispensing stand for dice embodying my new design;

FIG. 2 is a rear elevational view thereof;

FIG. 3 is a side elevational view thereof;

FIG. 4 is a cross sectional view taken on line 4—4 on FIG. 1;

FIG. 5 is a top plan view thereof;

FIG. 6 is a bottom plan view thereof.

The broken line representation of dice in FIGS. 1, 4 and 5 is for purposes of illustration only.

I claim:

The ornamental design for a combined display and dispensing stand for dice, as shown and described.
